PLATE CLAMP FOR PRINTING MACHINES

Harry V. Ball, Concord, Mass., and Frederick Lamatsch, Grantwood, N. J., assignors, by mesne assignments, to R. Hoe & Co., Inc., New York, N. Y., a corporation of New York

Application February 21, 1934, Serial No. 712,306

24 Claims. (Cl. 101—378)

This invention relates to plate clamping mechanism for rotary printing presses and more particularly to an improved clamping means having a removable actuating member for setting the clamping mechanism in a locked or unlocked position and in which the actuating member can only be removed when the clamping mechanism is in a locked position.

Various forms of plate locking devices have been devised which are adapted to be set in a locked or unlocked position by means of a tool which is removable from the device after either the locked or unlocked position has been reached. With such arrangements, it is possible for an operator to neglect to lock the plates before starting the machine, which condition would cause trouble.

According to the present invention an arrangement has been provided whereby a tool used with the plate clamping device for locking the plates can be removed from the plate clamp actuating member, only when the said plates are in a locked position and when removed will also cause the plate clamping device to be locked in its set position. The actuating tool, therefore, will serve three distinct purposes, one to move the plate clamps into a locked or unlocked engagement with the printing plates, another to provide a signal for the operator if the said tool is not removed from the plate clamping device, and another to set a locking mechanism which will lock the plate clamping device in its set position.

The reference to a "signal" is meant to signify, that when a tool is left in the clamping device, its exposed position will provide a signal or warning for the operator to lack the plate clamping mechanism and remove the tool before starting the machine in operation.

One object of the invention therefore is to provide an improved arrangement, whereby a tool used to actuate a plate clamping device can only be removed when the plate clamps are in locked engagement with the printing plates.

Another object is to provide a means whereby the plate clamping device is positively locked in its clamped position after the actuating tool is removed.

A still further feature of the invention is to provide an arrangement whereby the tool, used to actuate the clamping device, may be automatically ejected regardless of whether it is in a position which corresponds with a locked plate or an unlocked plate.

Other features include the combination of a clamping mechanism which is adapted to apply

an individual yielding pressure upon each plate clip or clamp by means of a single movement of an actuating member and the ease of application of the plate clamping mechanism to existing printing machines.

With the above and other objects not specifically referred to in view, the invention comprises certain novel arrangements which will be fully described in connection with the accompanying drawings and the novel features pointed out in the claims hereunto annexed.

In the drawings:

Figure 1 is an end elevation of a printing cylinder with a part broken away showing a portion of the plate locking device in a locked position; 15

Figure 2 is a fragmentary plan view looking at one end of the cylinder and showing a plate clamp in its locked position;

Figure 3 is a vertical section taken along line 3 of Figure 2;

Figure 4 is a section taken along the same line as Figure 3 but showing a continuing part of the clamping mechanism in clamping engagement with an inner plate;

Figure 5 is a fragmentary plan view similar to Figure 2, but showing the plate clamp in an open position;

Figure 6 is a vertical section taken along the line 6 of Figure 1 with parts broken away and showing the parts in a plate locking position and an operating tool partially inserted within the holder;

Figure 7 is a sectional view similar to Figure 6 on an enlarged scale showing the position of the various parts after the tool is completely inserted within the holder;

Figure 8 is a fragmentary plan detail with parts broken away and partly in section, looking in the direction of the arrow 8 of Figure 1 and showing the tool and holder in a position corresponding with the unlocked plate position;

Figure 9 is a fragmentary plan detail view similar to Figure 8 but showing the parts in a position which corresponds with the locked plate position;

Figure 10 is an end elevation of a printing cylinder with a part broken away and a part in section and showing a modified arrangement in which the operating tool may be automatically ejected, said tool being shown in a position corresponding with the locked plate position;

Figure 11 is a fragmentary plan view of the parts shown in Figure 10, looking in the direction of arrow 11;

Figure 12 is an enlarged fragmentary view sim-

iliar to Figure 11 with parts shown in section and in a position corresponding with a locked plate position;

5 Figure 13 is a view similar to Figure 12 with the parts in a position corresponding to an unlocked plate position; and

10 Figure 14 is a view similar to Figure 13 showing the position of the parts when the operating tool is being withdrawn.

15 Referring to Figures 1, 2, 3 and 4, the reference character 15 indicates a part of a printing or form cylinder and 16, 16a indicate stereotype plates mounted thereon at the end and intermediate portions thereof.

20 15 The means for locking said plates 16, 16a to the printing cylinder 15 comprises outer and inner plate clamps 17 and 18, each having beveled edges 17a, 18a which are adapted to engage correspondingly beveled edges on the plates 16, 16a. Said plate clamps are arranged so as to be quickly moved into engagement with the beveled edges of their respective plates, and after engagement therewith an additional spring pressure is applied which will provide a positive grip for the 25 clamp over its entire plate engaging surface.

25 20 To provide for the above conditions the said outer plate clamp is adjustably mounted on a screw 19, formed as a part of a bar 21, which clamp is adapted to slide within ways 22 formed in the surface of the cylinder in the usual well known manner. The outer end of said bar is provided with a reduced neck portion 23 and a head 24. At the end of the cylinder, a cam block 25 is provided which has a cam slot 20 in the lower surface thereof and is also slidably mounted within the ways 22. At the opposite end of said cam block a recess 26 is provided and a slot 27 is provided in the wall 28 at the end thereof.

30 25 The head 24 of the bar 21 is adapted to fit freely within the recess 26 and the reduced neck portion 23 will fit freely within the slot 27 in such manner as to permit a slight longitudinal movement of the bar in relation to the cam block. A washer 29 is also mounted on the neck portion 35 23 of the bar 21 and a heavy compression spring 31 is mounted over said bar between the washer 29 and a flange 32 on said bar. Openings 30 are provided in the flange 32 in which a rod or other tool may be inserted to rotate the screw 19 and thereby provide an adjustment for the plate clamp 17.

35 30 A cam roller 33 is mounted on a pin 34, which pin is carried by a movable segment 35, as shown in Figures 1 and 3, said segment being guided in a recess 36 provided in supports 37, which supports are secured to the end face of the printing cylinder 15. A peripheral movement is given to said segment 35 in both a clockwise and a counter-clockwise direction which movement causes the 40 cam roller 33 to move through the path provided by the cam groove 20 and thus moves the cam block in a forward or backward direction, to clamp or release the printing plate. Portions indicated at 39 are cut away to clear the cam block 25.

45 35 An elongated opening 40 is provided in the upper support 37 through which the grooved end of the cam block 25 is adapted to move when the same is reciprocated by the movement of the cam roller 33. The material at the outer periphery of the segment 35 and which forms the outer wall for the opening 40 is extended inwardly and longitudinally over the end of the cylinder 15 in the form of an annular flange 40'. The flange 40' 50 provides, adjacent the opening 40, a guide for

5 the cam block 25 and also the means to maintain the rollers 33 in cooperation with cam groove 20 thereof. The flange 40' extending as it does over the cylinder 15 and the parts at the periphery thereof and being disposed beneath the flange 40' 55 form a cover therefor to protect them against possible damage from external sources.

10 Three sets of plate clamping members are shown in Figure 1 for clamping the upper plates to the plate cylinder, each set of said clamping mechanism being simultaneously movable to a plate clamping position by the movement of the segment 35. Said segment is moved by means of a rocker arm 42 which is pivotally mounted upon a stud 43 secured to the support 37, as shown in Figures 1, 6 and 7, and has a socket 44 for the reception of an actuating tool 45. A hub 47, projecting from the upper end of the rocker arm 42, extends through an arcuate slot 48 in the support and has a further reduced end 49 on which a roller 51 is mounted. A recess 50 is provided in the segment 35 to receive the roller 51, and any movement of the rocker arm will cause a like movement of the segment 35. A guide bracket 52 is also provided which is secured to the support 37 and is shaped to form an outer guide wall 53 for the tool 45 and also has angularly disposed end walls 54 which provide stops to limit the motion of the rocker arm. It will be observed that the movement of the rocker arm between the 30 walls 54—54 of the guide bracket 52 is through a short arcuate path which thus provides for a quick locking action.

15 35 As previously stated one object of the invention is to provide means whereby the tool 45 can only be inserted or removed when the plate clamps 17, 18 are in locked engagement with the plates 16, 16a. To satisfy this condition two pins have been provided in the rocker arm 42, an upper locking pin 55 and a lower pin 56 as shown in Figures 6 and 7, each of which pins has an enlarged head portion and a stem portion and are slidably mounted within counterbored recesses 58 and 59 respectively.

20 40 Another locking pin 61, which cooperates with the lower pin 56, is slidably mounted in an opening 62 within the support 37 and comprises a main pin portion 63, a flange 64 and a stem 65. A compression spring 66 is tensioned between the flange 64 and a plug 67 in which plug, the end of the main pin portion 63 is also slidably mounted. The stem 65 therefore, of the pin 61, will normally be forced outward against the wall of the rocker arm 42 and when the said rocker arm is in the locked position, with the handle removed, the said stem 65 will project into the counterbore of the recess 59 to lock the said rocker arm from any further movement such as indicated in Figure 6.

25 45 A cam shaped recess 68 with an inclined surface is provided in the support 37 in the radial path of movement of the upper locking pin 55 as indicated in Figures 7, 8 and 9, and is so arranged that when the rocker arm is in the locked plate position the deepest portion of the recess 68 is opposite the head of said pin 55 and will thereby permit said pin to be forced into the recess 68 when the tool 45 is being withdrawn.

30 50 The tool 45 is provided with two cavities 70—70 on opposite sides thereof, and a stop pin 69 is positioned within said tool with its ends extending beyond each side thereof. The extending ends of pin 69 accurately position the tool 45 when inserted within the socket 44, to bring a cavity 70 into alignment with stem of the locking pin 55.

When the plate clamps 17 are in their locked position the rocker arm 42 is in the extreme left position as viewed from Figure 1, at which time the upper locking pin 55 will register with the deepest portion of the recess 68 and the lower pin 56 will register with the spring tensioned locking pin 61, as clearly shown in Figures 6 and 7. While in this position the operating tool 45 can either be inserted or withdrawn. Assuming that the said tool 45 is to be withdrawn from its actuating position, (Figure 7), the upward movement thereof will cause an inclined inner surface of one of the cavities 70 to force the locking pin 55 into the recess 68 in support 37 and also will cause the stem 65 of the spring tensioned locking pin 61 to be moved into locking engagement with the counterbore 59 as indicated in Figure 6. The rocker arm is thus locked and since the roller 51 on said rocker arm controls the position of the ring 35, the plate locking clamps will all be positively held in a plate locking position.

After a press operation has been completed and the printing plates are to be removed, the tool 45 is again inserted within the opening 44 in the rocker arm 42 and during its downward movement a beveled surface 72 at the end of the tool 45 will engage and force the stem of the pin 56 inward and thereby cause the head of said pin to engage and force the head of the pin 65 out of contact with the bore or recess 59 to release the stem 65 of the pin 61 from its locked engagement with the recess 59, such as shown in Figure 7.

The rocker arm 42 is then free to be moved by the tool 45, to the right as viewed in Figure 1 and thus cause the plate clamps 17 to be moved away from the printing plates 16 to permit said printing plates to be removed. During the latter movement, the rocker arm 42 will move from the position shown in Figure 9 to the position shown in Figure 8 and the pin 55 will be cammed out of the recess 68 as it is moved along the inclined surface 71 and then will move into locking engagement with the tool 45 as indicated in Figure 8. While in this position, the tool cannot be withdrawn and will thus serve as a signal for an operator signifying that the printing plates are in an unlocked position.

When the cam block 25 is moved inward by means of the movement of the roller 33 in engagement with the cam groove 20, the plate clamp 17 will have engaged the printing plate 16 through the movement of the bar 21 and will cause the flange 32 on the bar 21 to compress the spring 31, to thus bring the said plate clamp under the tension of the spring. The head 24 on said bar 21 will then occupy a position within the recess 26 about as shown in Figure 3.

In Figure 4, a connection is shown which cooperates with the movement of the plate clamp 17 to move the inner plate clamp 18 into engagement with the inner plate 16a, with the same pressure as that applied to the plate 16.

In Figures 10 to 14 an arrangement is shown whereby the tool 45 will be automatically ejected if the same should be left inserted in the rocker arm 42 when the press mechanism is started in operation. A safety device is thus provided to insure against oversight of an operator, who may possibly forget to lock a plate or remove a tool. With the automatic ejecting device, a tool will be withdrawn from its socket immediately after the press is started and in falling, will produce a noise which will be heard by the operator as the tool strikes the floor, whereupon the operator will quickly stop the machine. Due to the small por-

tion of a revolution through which the plate cylinder turns before the tool is ejected, no trouble would be caused by unlocked plates since the said plates have a normal gripping tension on the cylinder and are also held thereagainst by the inking rollers, so they could only be thrown off by centrifugal force, and this would be insufficient until a higher speed of the machine was reached.

In the said Figures 10 to 14, only such parts have been shown which comprise the ejecting features but it will be understood that the plate clamping mechanism (not shown) will be similar to that previously described. Such parts shown, which correspond with the parts previously described will be identified by the same reference characters with the suffix (a) included. It is to be noted also that the position of the rocker arm in relation to the locked or unlocked position is shown oppositely to that shown in the previously described figures.

The mechanism included in Figures 10 to 14 comprises a rocker arm 42a, a tool 45a inserted therein and a guide bracket 52a which are carried by a support 37a in a manner similar to that previously described.

The mechanism for ejecting the tool 45a from the rocker arm 42a, comprises a cam plate 80 secured to a stationary member 81, such as a part of the machine frame and positioned adjacent to the end of the printing cylinder. A cam surface 82 is provided on the upper edge of the cam plate and a roller or other projection 83 is provided at each side of the tool 45a. In the form of locking mechanism shown in Figures 10 to 14, a spring blade 84 is mounted within a recess 85 in the support 35a one end of said spring being secured to the wall at the inner surface of the recess and its opposite end being bent outward into alignment with the surface of the support 37a. When the rocker arm 42 is in a position which corresponds with the locked plate position such as viewed in Figures 10, 11 and 12, the locking pin 55a is free to slide into the recess 85 to thus permit the said tool to be easily withdrawn.

When said rocker arm 42 is in the opposite position, a position which corresponds with the unlocked plate position such as in Figures 13 and 14, the free end of the spring blade 84 will hold the pin 55a in a locked engagement with the cavity 70a in the tool 45a.

If the press operation should be started at a time when the tool 45a is in the rocker arm 42, in either of the above described positions, the same will be ejected after the roller 83 engages the cam 82, regardless of whether the said tool is in a locked or unlocked position, the ejecting force being sufficient to overcome the strength of the spring tension when in a locked position. The dotted line illustration of the plate 80, indicates its position for use with cylinders rotating in an opposite direction to that indicated by the arrow. Said spring tension, however, will be sufficient to prevent the manual withdrawal of said tool 45a unless unusual force is exerted.

It will be understood that the invention may be embodied in other specific forms without departing from the spirit or essential attributes thereof, and it is therefore desired that the present embodiment be considered in all respects as illustrative and not restrictive, reference being had to the appended claims rather than to the foregoing description to indicate the scope of the invention.

What we claim is:

1. The combination with a mechanism for ac- 75

tuating longitudinally movable plate clamps on a printing cylinder, of a manually controlled member to actuate said clamps, a removable tool cooperating therewith, means to prevent the withdrawal of said tool when the plate clamps are in an unlocked position, and means for locking the manually controlled member when the tool is withdrawn.

2. The combination of a plate holding cylinder 10 having longitudinally movable plate clamps, a manually actuated rocker member to move said plate clamps to a plate locking position, a removable tool to operate said rocker member, and locking means cooperating with said rocker member 15 and tool to permit the removal of the said tool only when the plate clamps are locked and to lock the rocker arm upon the removal of said handle.

3. The combination of a plate holding cylinder 20 having longitudinally movable plate clamps thereon engaging the edge of a plate adjacent the end of the cylinder, means to simultaneously move all of said clamps to a clamping position, a spring tensioned follow up member on each individual 25 clamp, a rocker member cooperating with the simultaneously movable means, a removable tool to actuate said rocker member, and a slidably means carried by the said rocker member to prevent the withdrawal of said tool by releasable engagement therewith when the plate clamps 30 are unlocked.

4. The combination of a plate holding cylinder having longitudinally movable plate clamps thereon, means to simultaneously move all of 35 said clamps to a clamping position and a spring tensioned follow up member on each individual clamp, a rocker member cooperating with the simultaneously movable means, a removable tool to actuate said rocker member, means to prevent the withdrawal of said tool when the plate clamps 40 are unlocked, and means to lock the rocker member when the tool is withdrawn.

5. The combination of a plate holding cylinder 45 having longitudinally movable plate clamps thereon, a peripherally movable segment arranged to move the plate clamps into or out of a plate clamping position, a manually actuated rocker member to actuate said movable segment, a removable tool to actuate said rocker member, and locking means cooperating with said rocker member 50 and tool to permit the removal of said tool only when the plate clamps are in locked engagement with the plate.

6. The combination of a plate holding cylinder 55 having longitudinally movable plate clamps thereon, a peripherally movable segment arranged to move the plate clamps into or out of a plate clamping position, a manually actuated rocker member to actuate said movable segment, a removable tool to actuate said rocker member, and locking means cooperating with said rocker member 60 and tool to permit the removal of said tool only when the plate clamps are in locked engagement with the plate, and means to lock the rocker arm upon the removal of said handle.

7. The combination of a plate holding cylinder 70 having longitudinally movable plate clamps engaging the edge of a plate adjacent the end of the cylinder, a peripherally movable segment having an annularly disposed flange extending longitudinally over said cylinder end, cam rollers mounted on the periphery of said segment beneath said flange, cam blocks, disposed beneath said flange and engaged and actuated by said 75 cam rollers, a yieldable connection between said

cam blocks and plate clamps, and a manually actuated member to actuate said peripherally movable segment.

8. The combination of a plate holding cylinder 5 having longitudinally movable plate clamps, a peripherally movable segment, cam rollers mounted on the periphery of said segment, cam blocks engaged and actuated by said cam rollers, a yieldable connection between said cam blocks and plate clamps, a rocker arm connected in driving 10 relation with said peripherally movable segment, a removable tool to actuate said rocker arm, and locking means cooperating with said rocker arm and tool to permit the removal of the said tool only when the plate clamps are locked and to 15 lock the rocker arm upon the removal of said tool.

9. The combination of a plate holding cylinder 20 having longitudinally movable plate clamps, a manually actuated rocker member to move said plate clamps to a plate locking position, a removable tool for said rocker member, and a slidably pin cooperating with said rocker member to prevent the withdrawal of the tool when the plate 25 clamps are unlocked.

10. The combination of a plate holding cylinder 30 having longitudinally movable plate clamps, a manually actuated rocker member to move said plate clamps to a plate locking position, a removable tool for said rocker member, a slidably pin 35 cooperating with said rocker member to prevent the withdrawal of the tool when the plate clamps are unlocked, and a spring tensioned member to lock the rocker member when the tool is withdrawn.

11. The combination of a plate holding cylinder 40 having longitudinally movable plate clamps thereon, a manually actuated rocker member to move said plate clamps to and from a plate clamping position, a support for said rocker member, a removable tool for said rocker member, a spring tensioned pin in said support, and a slidably pin in said rocker member, said pins adapted to cooperate with the tool, one pin to lock said tool when it is in a position which agrees 45 with an unlocked plate position and the other pin to unlock the rocker member when the tool is in a position which agrees with the locked plate position.

12. An arrangement for actuating and locking 50 plate clamps to printing plates on a printing cylinder, comprising a rocker arm, a support for said rocker arm and a removable tool to actuate said arm, a pin slidably mounted within the arm adapted to lock the tool when in an unlocked 55 plate position, and a spring tensioned pin mounted within the support adapted to engage the rocker arm to lock same in its set position after the tool is withdrawn.

13. An arrangement for actuating and locking 60 plate clamps to a printing cylinder, comprising a rocker arm, a support for said rocker arm and a removable tool to actuate said arm, a pin slidably mounted within said arm adapted to engage a cavity in the tool and be locked therein when the 65 tool is in an unlocked plate position and adapted to be cammed outward into a recess in the support when the tool is in a locked plate position.

14. An arrangement for actuating and locking plate clamps to a printing cylinder, comprising a 70 rocker arm, a support for said rocker arm and a removable tool to actuate said rocker arm, two pins slidably mounted within said arm, one pin cooperating with a recess in the support and a cavity in the tool to release and lock said tool 75

- when in a plate clamped or unclamped position respectively, and another pin cooperating with a spring tensioned pin in said support to lock the rocker arm when the tool is removed.
- 5 15. In combination with a mechanism for locking printing plates on a printing cylinder, a manually movable member to actuate said mechanism, a removable tool cooperating therewith, and means for automatically ejecting the tool from said manually movable member when the printing cylinder is rotated.
- 10 16. In combination with a mechanism for locking printing plates on a printing cylinder, a manually actuated rocker arm carried by said cylinder, a removable tool in operating engagement with said rocker arm, a roller on said tool, and a cam member positioned in the path of said roller, whereby, upon the rotation of said printing cylinder, the cam member will be engaged by the roller and the tool will be ejected from the rocker arm.
- 15 17. In combination with a mechanism for locking printing plates on a printing cylinder, a support on said cylinder and a rocker arm pivotally mounted upon said support, a removable actuating tool for said rocker arm, a flat spring member positioned within a recess in the support, and a pin slidably mounted in the rocker arm, said pin being adapted to be held in locked engagement with a cavity in the tool when the spring member engages same to prevent the tool from being manually withdrawn when the printing plates are unlocked and also being adapted to be positioned out of contact with said tool when the printing plates are in a locked position to permit said tool to be withdrawn.
- 20 18. In combination with a mechanism for locking printing plates on a printing cylinder, a support on said cylinder and a rocker arm pivotally mounted upon said support, a removable actuating tool for said rocker arm, a flat spring member positioned within a recess in the support and a pin slidably mounted in the rocker arm, said pin being adapted to cooperate with the spring and recess to yieldably lock the tool in the rocker arm when the plates are in an unlocked position and to release said tool for withdrawal when the plates are in a locked position, a cam plate positioned adjacent said cylinder, and a member on said tool adapted to be engaged by said cam to eject the tool when the cylinder is rotated.
- 25 19. The combination of a plate holding cylinder having longitudinally movable plate clamps engaging the edge of a plate adjacent the end of the cylinder, a peripherally movable segment, cam rollers mounted on the periphery of said segment, cam blocks engaged and actuated by said cam roller, a yieldable connection between said cam blocks and plate clamps, and means whereby the position of each clamp and yieldable con-
- nection may be adjusted to accommodate various sizes of plates while the plates are in position on the cylinder.
- 20 20. In a mechanism for actuating longitudinally movable plate clamps on a printing machine, a movable member to actuate said clamps, a removable tool for moving said member, means to resist but not prevent the removal of said tool when the plate clamps are in unclamped position, and means to lock said clamp actuating member when the tool is removed.
- 25 21. The combination of a plate holding cylinder having a plurality of longitudinally movable plate clamps thereon, means to simultaneously move all of said clamps to a plate clamping position, a rockable member to operate said plate moving means, a tool freely movable into association with said rockable member to actuate the same, and means associated with said rockable member to resist but not prevent the removal of said tool when the plate clamps are in unclamped position.
- 30 22. The combination of a plate holding cylinder having a plurality of longitudinally movable plate clamps thereon, means to simultaneously move all of said clamps to a plate clamping position, a rockable member to operate said plate moving means, means to lock said rockable member in one position, a tool movable into association with said rockable member to unlock and to actuate the same, and means carried by said rockable member to resist the removal of said tool when the plate clamps are in unclamped position.
- 35 23. The combination of a plate holding cylinder having a longitudinally movable plate clamp thereon, means to move said clamp into plate clamping position, a rocker member cooperating with said clamp moving means to actuate the same, a removable operating member engaging said rocker member to actuate it, and freely slidably means carried by one of said members and engageable by the other to resist the removal of said operating member when said clamp is in plate unclamping position.
- 40 24. The combination of a plate holding cylinder having a longitudinally movable plate clamp thereon, a member mounted for movement peripherally about said cylinder and having an annular flange extending longitudinally over said cylinder, a cam roller mounted on said member beneath said flange, a cam block slidably mounted on said cylinder and extending beneath said flange and guidingly engaged thereby to maintain it in engagement with said cam roller, and a manually actuatable member to peripherally move said first member about said cylinder.
- 45

HARRY V. BALL.
FREDERICK LAMATSCH. 60
